To all whom it may concern:

Be it known that I, CHARLES EDWARD HAVILAND, a citizen of the United States, residing at Limoges, in the Republic of France, have 5 invented and produced a new and original Design for a Cup or Similar Article, of which the following is a specification, reference being had to the accompanying drawings, forming a part thereof, and in which—

In the drawings, A designates the cup, whose body has the downwardly-converging curved side surfaces, and which body, adjacent to its upper edge, bears the scalloped ornamental scroll configuration B, as shown. Extending downward from the points intermediate the scallops of the configuration B are the depressed surfaces or grooves C. 20 25
